Suffield, Conn. 06078

Filed Mar. 20, 1967, Ser. No. 6,306

Term of patent 14 years

(Cl. D61—1)

FIG. 1.

FIG. 2.

FIG. 3.

FIG. 4.

FIG. 5.

FIG. 1 is a front elevational view of a film reel embodying my new design;

FIG. 2 is a top plan view thereof;

FIG. 3 is an enlarged fragmentary front elevational view of a pair of the spiral guides of the film reel embodying my new design;

FIG. 4 is a fragmentary side elevational view, partly in cross-section, taken through one of the spiral guides on line 4—4 in FIG. 3;

FIG. 5 is a top plan view of the spiral guides of FIG. 3.

The rear not shown is substantially a mirror image of the front shown in FIG. 1.

The fragmentary broken line showing of a photographic film in FIG. 3 is for illustrative purposes only.

I claim:

The ornamental design for a film reel, as shown and described.
